TOY DOLL

Terrance R. Mitchell, St. Paul, Minn., assignor to Cortez
Industries, Inc., Minneapolis, Minn.

Filed Jan. 31, 1973, Ser. No. 328,328

Term of patent 14 years

Int. Cl. D21—01

U.S. Cl. D34—4 R

FIG. 1 is a front, perspective view showing my toy doll design;

FIG. 2 is a front, elevation view of the toy doll of FIG. 1;

FIG. 3 is a side, elevation view of the toy doll of FIG. 1;

FIG. 4 is a rear, elevation view of the toy doll of FIG. 1;

FIG. 5 is a top, plan view of the toy doll of FIG. 1;

FIG. 6 is a bottom, plan view of the toy doll of FIG. 1; and

FIG. 7 is a front, perspective view showing a modified version of my toy doll design without a hat.

I claim:

The ornamental design for a toy doll, as shown and described.
